UNITED STATES PATENT OFFICE.

GEORGE REITER, OF ALLEGHENY, ASSIGNOR TO THE PITTSBURG TUBULAR STEEL WHIFFLETREE COMPANY, OF PITTSBURG, PENNSYLVANIA.

MANUFACTURE OF WHIFFLETREES AND DRAFT-BARS.

SPECIFICATION forming part of Letters Patent No. 407,837, dated July 30, 1889.

Application filed February 15, 1889. Serial No. 300,046. (No model.)

To all whom it may concern:

Be it known that I, GEORGE REITER, of Allegheny, in the county of Allegheny and State of Pennsylvania, have invented a new 5 and useful Improvement in the Manufacture of Whiffletrees and Draft-Bars; and I do hereby declare the following to be a full, clear, and exact description thereof.

My invention relates to the manufacture of 10 whiffletrees, neck-yokes, and other draft-bars for carriages, wagons, and other vehicles, its object being to provide a method of making metal draft-bars which shall be light in weight, and yet shall possess all the necessary strength 15 for such purposes. It is well known that the metal draft-bar has great advantages over the ordinary wooden bar in that it is not only more durable, but in that the fittings and trimmings can be more permanently secured 20 thereto. The most improved form of metal draft-bar heretofore in use has been made of wrought-metal tubing tapered and gradually reduced from at or about its middle portion toward the ends thereof, it being found that 25 by tapering the tube toward the ends its strength is very considerably increased. These tubular draft-bars have, however, been found to be objectionable in that they were heavier than desirable in order to obtain the 30 necessary stiffness or power to resist the bending strain.

The object of my invention is to provide means of forming whiffletrees or draft-bars which, while possessing the necessary stiffness and strength, can be formed of tubing of 35 less thickness and diameter than that heretofore employed, so materially reducing both the weight and the cost of the article.

To these ends my invention consists, generally stated, in forming the bodies of these whiffletrees or draft-bars by tapering a wrought-metal tube from its middle portion toward the ends thereof, and then flattening part or all of the blank so obtained, thus 45 imparting to the body a flat or oval shape in cross-section, it being found that in so doing the strength and stiffness of the draft-bar in the direction of the strain thereon are increased one-fifth or more, and consequently 50 that the same strength of draft-bar can be obtained from a much lighter tube.

To enable others skilled in the art to practice my invention, I will describe the same more fully, referring to the accompanying drawings, in which—

55

Figure 1 is a side view of the tube from which the draft-bar is to be formed. Fig. 2 shows the tapered blank. Figs. 3 and 4 are edge and side views, respectively, of the draft-bar, both tapered and flattened. Fig. 5 is an enlarged central cross-section of the blank before flattening. Figs. 6 and 7 are enlarged cross-sections of the finished draft-bar at the points 11 and 22, respectively. Figs. 8 and 9 are views of the dies employed for flattening the 65 tapered blank, and Fig. 10 is a view of the finished whiffletree having the fittings or trimmings thereon.

Like letters of reference indicate like parts in each figure.

70

In forming a whiffletree-body or draft-bar in accordance with my invention I take the wrought-metal tube corresponding in sectional area to the middle or largest portion of the finished draft-bar, and by means of suitable dies—such as are known in the art—I taper the same from at or near the center toward the ends, the custom being to leave a small portion in the middle of the draft-bar straight or free from taper to receive the central fitting, this middle portion being shown at *a*, and the tapered portions generally extending therefrom to the ends of the tube, as shown at *b*. After having imparted the taper to the tube, forming the blank shown in Fig. 2, I then flatten the blank, so as to form the whiffletree-body or draft-bar, as shown in Figs. 3 and 4. This bar may be flattened throughout any desired portion thereof—such, for example, as throughout its entire length or simply between the ends, the bar shown being flattened between the points *c* *c*, and being cylindrical and tapering from the points *c* to the ends *d*, this being shown by the cross-sections in Figs. 6 and 7. I prefer this form of bar, for 90 the reason that I obtain the necessary strength in the central portion of the blank and stiffness in the entire body thereof, as the greater portion thereof is increased in width in the direction of greatest strain thereon, and at the 95 same time the curvature of the side walls of the tube is so reduced as to brace it in the di-

rection of the strain, so that the strain is more easily sustained thereby, and as the end portions of the bar, which remain cylindrical, are considerably reduced in diameter and increased in thickness in the tapering of the blank the necessary strength and stiffness are obtained in the end portions thereof without flattening, while I am enabled to employ cylindrical fittings for the ends of the blank, as shown in Fig. 10, this shape of fittings being more easily applied. The blanks can be flattened in any suitable way, that shown in the drawings being by the employment of the dies shown in Figs. 7 and 8, which correspond in shape and contour to the outer contour to be imparted to the body of the whiffletree or draft-bar. The dies shown in the end portions, as at *e*, are semi-cylindrical for the purpose of holding the end portions of the blank cylindrical, as shown in Fig. 3, and the main body of the die is formed of such shape as to flatten the blank when compressed therein, this being more clearly shown by the cross-section Fig. 7, in the middle portion of the die. When the draft-bar is employed for whiffletrees, I generally use therewith the fittings or trimmings shown in Fig. 10, the central fitting *h* being formed of a sleeve or collar corresponding in shape to the flattened blank and secured thereon by shrinking, the sleeve having the rings *i* or other engaging device in line with the greatest diameter of the draft-bar in order to hold it in proper position to sustain the greatest strain. The fittings employed, however, form no part of my present invention, and any suitable fittings may be employed with the draft-bar.

It is found that a draft-bar formed in accordance with my invention possesses very

much greater stiffness and strength than a 40 bar formed from the same size and weight of tube where it is not flattened, the tapered and flattened draft-bar sustaining a strain of twenty per cent. or more over the ordinary tapered tube, and for this reason the draft-bars can be formed of a tubing having thinner walls and being smaller in diameter, and consequently the weight of the draft-bar can be very materially reduced, the ordinary singletree being reduced about two pounds in 45 weight and the weight of the doubletree being reduced in proportion and weighing but little more, if any, than the ordinary wooden draft-bar. As the cost of flattening the blanks is comparatively small, there is therefore a 50 large saving in the cost of the finished draft-bar.

What I claim as my invention, and desire to secure by Letters Patent, is—

1. The herein-described method of forming 60 the bodies of whiffletrees or draft-bars, consisting in tapering a wrought-metal tube from its middle portion toward the ends and then flattening part or all of the blank so obtained, substantially as and for the purposes set forth. 65

2. The herein-described method of forming the bodies of whiffletrees or draft-bars, consisting in tapering a wrought-metal tube from its middle portion toward the ends and then flattening said blank between the ends thereof, 70 leaving the ends cylindrical, substantially as and for the purposes set forth.

In testimony whereof I, the said GEORGE REITER, have hereunto set my hand.

GEORGE REITER.
